US0D1107688S

(12) **United States Design Patent** (10) **Patent No.:** **US D1,107,688 S**
(45) **Date of Patent:** **** Dec. 30, 2025**

(54) **CASE**

(71) Applicant: **Urban Armor Gear, LLC**, Laguna Niguel, CA (US)

(72) Inventor: **Hyun Hong**, Murrieta, CA (US)

(73) Assignee: **Urban Armor Gear, LLC**, Laguna Niguel, CA (US)

(**) Term: **15 Years**

(21) Appl. No.: **29/946,126**

(22) Filed: **Jun. 6, 2024**

Related U.S. Application Data

(62) Division of application No. 29/843,790, filed on Jun. 23, 2022, now Pat. No. Des. 1,035,631.

(57) **CLAIM**

The ornamental design for a case as shown and described.

DESCRIPTION

FIG. 1 is a front right perspective view of a case of my design.

FIG. 2 is front left perspective view of the case of FIG. 1.

FIG. 3 is a back perspective view of the case of FIG. 1.

FIG. 4 is a front view of the case of FIG. 1.

FIG. 5 is a back view of the case of FIG. 1.

FIG. 6 is a first side view of the case of FIG. 1.

FIG. 7 is second side view of the case of FIG. 1.

FIG. 8 is a top view of the case of FIG. 1; and,

FIG. 9 is a bottom view of the case of FIG. 1.

The broken lines shown in the figures are included for the purposes of illustrating portions of the case and form no part of the claimed design. Randomly dashed lines represent surface shading.

1 Claim, 7 Drawing Sheets
